COMBINED TELEPHONE SUPPORT AND MEMO
PAD HOLDER OR THE LIKE

Michael Marder, 277 E. 207th St., Bronx, N.Y.

Filed Feb. 8, 1963, Ser. No. 73,490

Term of patent 14 years

(Cl. D74—1)

FIG. 2

FIG. 1 is a perspective front view of a combined telephone support and memo pad holder or the like, showing the invention; and

FIG. 2 is a right hand side view of the combined telephone support and memo pad holder or the like of FIG. 1.

I claim:

The ornamental design for a combined telephone support and memo pad holder or the like, as shown.
